VALVE CONTROL MECHANISM

Lee G. Daniels, Rockford, Ill., assignor to Automatic Pump & Softener Corporation, Rockford, Ill., a corporation of Illinois

Original application November 20, 1933, Serial No. 698,829. Divided and this application August 18, 1937, Serial No. 159,736

8 Claims. (Cl. 161—7)

This application is a division of my copending application Serial No. 698,829, filed November 20, 1933, now Patent Number 2,110,758.

This invention relates to control mechanisms generally and while herein disclosed as applied to the operation of an automatic water softener valve is applicable wherever a predetermined succession of movements of a valve, switch, or the like, is desired.

The principal object of my invention is to provide a control mechanism using a timing mechanism including a clock type motor, the circuit through which is closed when the cycle of movements is begun and which maintains the timing mechanism in operation throughout the cycle of movements causing second and third movements to occur in a predetermined timed relationship with respect to the commencement of the cycle and thus insure an accurately timed operation. The timing mechanism in accordance with the invention is electrically connected with a mechanism operated by a second or main motor to cause operation of the mechanism at the proper intervals, for example, to move the valve from salt wash position to rinse position and thereafter from rinse position back to softening position. The clock type motor operating the timing mechanism has its circuit broken when the timing mechanism has made a complete turn and is back to starting position. The circuit is closed by a suitable switch at the start of the cycle which keeps the motor running until the switch is operated by the timing mechanism at the end of its movement to break the motor circuit.

This and other objects of the invention will soon appear as reference is made to the accompanying drawings, wherein—

Figures 1 and 2 are vertical sections in planes at right angles to one another through a control mechanism made in accordance with my invention;

Fig. 3 is a sectional detail of the timer on the broken line 3—3 of Figure 1;

Fig. 4 is an electrical diagram of the control mechanism;

Figs. 5 and 6 are views of the main portion of Fig. 4 showing the parts in other positions;

Fig. 7 is a diagram similar to Fig. 4 but showing a different control mechanism, and

Fig. 8 is a sectional detail on the line 8—8 of Fig. 7.

Similar reference numerals are applied to corresponding parts throughout the views.

While I have disclosed the control mechanism as applied to the operation of a valve, it will, of

course, be understood that the invention is not limited to that application but may be applied to any valve, switch or the like requiring a predetermined succession of movements in a similar manner. Furthermore, while the particular valve herein shown is designed for use with an automatic or semi-automatic water softener, it should be evident that the valve operated by the control mechanism may be employed for any one of a large number of other purposes, wherever an apparatus, machine, or the like, requires a similar succession of valve movements. Then, too, while the valve shown has three valve members on a single stem that is reciprocated in the operation of the control mechanism, it is obvious that the valve operated by the control mechanism might be equipped with any number of valve elements and that the valve that is operated need not necessarily be of the reciprocatory type inasmuch as the reciprocatory movement of the operated member of the control mechanism might easily be converted into rotary movement of the operated valve member. The claims should be construed accordingly.

Referring first in a general way to Fig. 4, the numeral 10 designates the upper half of the one-piece body of the valve forming the subject matter of the parent application above identified. 11 is the single stem extending lengthwise of the body and projecting from the upper end thereof for reciprocatory movement by and under the control of the mechanism of the present invention indicated generally by the numeral 12. The latter operates the valve automatically or, to be more specific, semi-automatically inasmuch as the mechanism disclosed depends upon the operator closing a switch to throw the softener into regeneration. Of course, the invention is not limited to semi-automatic operation inasmuch as there are numerous ways of taking care of the closing of the switch automatically, as for example, by means of a clock. At 13 is indicated a softener tank and at 14 a brine tank. The valve body 10 has upper and lower hollow casing portions 15 and 16 providing passages therein for controlling the flow of water and brine through the softener in accordance with the positions of the valve stem 11 which determines the closing and opening of the three valve members, numbered 17—19, carried on said stem. The valve 17 is a poppet type valve rigid with the stem and arranged to engage a seat 20 to close off communication between chambers 21 and 22 in the casing 15. A pipe 23 communicates with the chamber 21 and has connection with the top of

the softener tank 13 as well as with the service pipe 24. A check valve 25 is preferably provided in the service pipe seating in the direction of the softener. A pipe 26 communicates with the chamber 22 and leads to the sewer, or any suitable drain receptacle. The valve 18 is a plunger or piston type valve and controls communication between the chambers 36 and 37 in casing 16. 41 is an injector nozzle, the inlet end of which communicates with the chamber 36. The pipe 44 provides communication between the chamber 37 and the bottom of the softener 13, and a pipe 45 supplies hard water to the chamber 36. The valve 19 is a poppet type valve for closing off communication between the chamber 37 and the pipe 48 that communicates with the bottom of the brine tank 14, and as described in the parent application, this valve has a lost motion connection with the stem 11.

In operation, assuming the valve is in the softening position as shown in Fig. 4, hard water supplied through the pipe 45 flows through chamber 36 and chamber 37 to the pipe 44 and enters the bottom of the softener 13 for passage upwardly through the zeolite therein. The softened water leaves the top of the softener 13 through pipe 23 and is delivered to the service system through pipe 24 which branches off from the pipe 23. When the zeolite in the softener requires regeneration the valve stem 11 is raised, as illustrated and described in the parent application, unseating valves 17 and 19 and closing valve 18. Under these conditions, the valve 18 being closed, the hard water supplied through pipe 45 flows through passage 36 and is discharged through the injector nozzle 41. The injector action results in a reduction in pressure in the chamber 37 sufficient to draw brine from the tank 14 through the pipe 48 past the open valve 19, and this brine is delivered by the hard water through the pipe 46 to the bottom of the softener 13 for passage upwardly through the zeolite for regeneration of the latter. The waste water containing released calcium and magnesium from the zeolite leaves the top of the softener through pipe 23 and is carried to the drain through pipe 26 past the open valve 17. It is during this operation that the check valve 25 functions to prevent draining water from the service system through pipes 23 and 26. After a predetermined amount of brine has been passed through the softener, the amount being determined as hereinafter explained by the continuance of the salt wash for a predetermined period of time, the valve stem 11 is lowered to an intermediate or rinse position, closing the valve 19 but leaving the valve 17 open and valve 18 closed. Under these conditions, the hard water delivered through pipe 45 is conducted through pipe 44 to the bottom of the softener 13 without entraining any brine, due to the fact that the valve 18 has been closed to cut off communication with the brine tank 14. The hard water passing up through the zeolite in the softener rinses out the brine and any remaining released calcium and magnesium and is conducted through pipes 23 and 26 to the drain. After a predetermined period of rinsing, the valve stem 11 is moved back to the position shown in Figure 4 for softening operation, closing the valve 17 and opening the valve 18, and, of course, leaving the brine valve 19 closed. Upflow is used in all operations of softening, salt washing, and rinse. It is, of course, apparent that by simply reversing the connections of pipes 23 and 44 with the softener 13 one would secure down-

flow softening, downflow salt washing, and downflow rinsing. Any suitable provision may be made for maintaining a certain level in the brine tank 14. A hand operated valve is shown at 56 which can be opened to conduct hard water from the supply pipe 45 through the pipe 57 discharging into the brine tank.

Referring now more particularly to Figs. 1-3, 5 and 6, the arms 58 shown in Figure 1 are preferably cast integral with the body 10 of the valve and have the base plate 59 of the motor driven mechanism 60 for power operation of the valve 11 secured thereon. The mechanism 60 is a part of the control mechanism previously referred to and designated generally by the numeral 12. The mechanism 60, briefly stated, comprises a motor 61 which, through reduction gearing 62, is adapted to intermittently communicate rotation to the shaft 63, whereby to turn a cam 64 provided for moving the valve stem 11. A plunger 65 has rollers 66 thereon riding on the periphery of the cam 64, and the lower end of the plunger is made tubular to receive and make connection with the upper end of the valve stem 11. A cross-pin 67 on the stem extends through slots 68 in the side walls of the tubular portion of the plunger to provide a lost motion operating connection. A coiled compression spring 69 fitting in the tubular portion of the plunger engages the upper end of the stem 11 and tends normally to urge it downwardly, whereby to hold the valve 17 seated under a certain pressure. When the plunger 65 is moved upwardly by the turning of the cam 64 with the shaft 63, the cross-pin 67 reaches the lower end of the slots 68 so that the valve stem is moved upwardly with the plunger. Contrariwise when the plunger moves downwardly, the valve stem 11 moves with it up to the time that the valve 17 engages its seat, after which the further movement of the plunger merely places the spring 69 under additional compression so as to increase the pressure applied to the valve 17, holding the same seated. There are four other cams 70-73 on the shaft 63. These turn with the shaft in the turning of the cam 64 and are arranged to operate contacts 70'-73' for controlling the electric circuit for the motor 61. The cam 72 differs from the other cams 70, 71 and 73 in that it is circular and has three notches provided in the periphery thereof into which the follower for the contacts 72' is arranged to drop, as shown in Fig. 1, to break the motor circuit. While the follower is riding on the periphery of this cam from one notch to another, the motor circuit is kept intact. This cam, therefore, predetermines the stopping of the motor; the other three cams, as will soon appear, control the starting of the motor. It will be observed that the three notches in the cam 72 are 90° apart and, noting the direction of rotation indicated by the arrow, it follows that once the motor starts to operate from the position shown, the first operation will be sufficient to move the cam 64 through 180°. Then, on the next operation, the cam 64 will be moved 90°, and on the following operation another 90° back to its starting point. In the 180° movement of cam 64, valve stem 11 is moved from softening position (Fig. 4) to salt wash position. In the following 90° of movement, the valve stem 11 is moved back again part way toward its original position to rinse position, and in the following 90° of movement the valve stem 11 is moved the rest of the way to its original softening position. There are numerous ways of causing the motor 61 to go through the three op-

erations to move the valve from softening to salt wash, from salt wash to rinse, and from rinse back to softening position. I show a semi-automatic mechanism in which a switch 74 is closed by the operator to start the cycle when it becomes apparent that the softener requires regeneration, but instead of this some means such as a clock might be provided for automatically starting the cycle or any other means of an automatic character might be provided for closing the circuit either when a predetermined amount of water has been softened or when the outgoing water shows signs of hardness. The additional mechanism for initiating the second and third operations of the motor 61, following this first mentioned operation, can also take various forms, but I prefer a mechanism using a self-starting clock type motor 75 driving a timer 76 through suitable reduction gearing 77. I shall now describe this mechanism in detail.

A casing 78 houses the timer 76, together with its drive motor 75 and reduction gearing, and is supported on a cover 79 which is suitably locked detachably on the base 59 of the mechanism 60. The timer 76 has two contact brushes 80 and 81 adjustably mounted on the rotatable body thereof, the former disposed in one plane and extending to a certain radius and arranged to be clamped in adjusted position by means of a screw 82 entered in the arcuate slot 83, and the other disposed in another plane and projecting to a larger radius and arranged to be clamped in adjusted position by means of a screw 84 entered in the arcuate slot 85. The contact brush 80 is arranged to wipe and ride over a terminal 86 disposed at the proper radius with respect to the timer and reaching only to the plane of the brush 80. Another terminal 87 cooperates with the brush 81 in a similar fashion. The arrangement is such that the brush 80 will engage only the terminal 86 and the brush 81 will engage only the terminal 87 in the turning of the timer. The brushes are adjusted to such angular relationship with respect to one another that there will be a predetermined period of salt washing measured by the time it takes the brush 80 to reach the terminal 86, and so that there will be a predetermined rinse period measured by the time it takes beyond that point for the brush 81 to reach the terminal 87. A brush 88 rides on the periphery of the timer and completes the circuit for motor 61 either upon engagement of brush 80 with terminal 86 or engagement of brush 81 with terminal 87, as will soon appear. A mercoid switch 89 is pivoted in the casing 78 at 90 with its free end resting normally on the upper end of the plunger 65 so that the mercury pool is away from the terminals thereof. However, when the plunger 65 is raised by reason of a half turn of the cam 64, as shown in Fig. 5, the free end of the switch 89 is raised with it, thus causing the mercury pool to run to the other end of the tube and close a circuit through the terminals to start the motor 75. A latch 91, pivoted at 92, is normally urged to move in a clockwise direction under the action of a tension spring 93, and has a ledge 94 on which the free end of the switch 89 is arranged to be supported when the parts are in the position shown in Fig. 6. The latch 91 is held out of the way of the switch 89 at the commencement of the cycle by a pin 95 projecting from the timer 76. How-

ever, as soon as the switch 89 is raised, thus closing the circuit for motor 75, the timer 76 turns and the pin 95 is moved past the latch, allowing the latter to swing in a clockwise direction toward the switch so that the ledge 94 comes into position under the free end of the switch. 5 The switch is, therefore, supported when the plunger 65 moves downwardly to the rinse position shown in Fig. 6, thus maintaining the circuit for motor 75 intact. Later, when the rinse is completed, that is, after the brush 81 has engaged the terminal 87, as shown in Fig. 6, the pin 95 approaches the latch 91 in the continued turning of the timer 76 and moves the latch in a counterclockwise direction away from the switch 89. The latter being no longer supported by the ledge 94 drops down onto the upper end of the plunger 65 and breaks the circuit for motor 75, thus bringing the timer 76 to a standstill with the pin 95 holding the latch 91 in the position shown in Figs. 1 and 4. Before proceeding to the description of the operation of the control mechanism, attention is called to the fact that the motors 61 and 75 are connected across the secondary of a transformer 96, which in turn has its primary connected across the usual 110 volt line. 10 15 20 25 30 35 40 45 50 55 60 65 70 75

In operation, when the softener is to be regenerated, the operator closes switch 74, thus completing a circuit through motor 61 by reason of the fact that the contacts 73' are, at the time, held closed by cam 73. The operator holds the switch 74 closed just long enough to get the motor started, the circuit being kept intact thereafter by reason of the closing of contacts 72' by the cam 72, the direction of rotation of which is indicated by the arrow in Fig. 4. The motor 61 will continue to operate until it has turned the cam 64 with the shaft 63 through 180° whereupon the follower engaging the cam 72 drops into the notch and opens the contacts 72'. The valve stem 11 has accordingly been raised from the softening position to the salt wash position, as indicated in Fig. 5, and mercoid switch 89 has been raised with the valve stem 11 so as to start the motor 75 and cause the timer 76 to turn for timing of the salt wash and rinse. The cam 71, having turned through 180° with the cam 64, has closed contacts 71'. The salt wash continues for that period of time that it takes for the brush 80 to travel from the position shown in Fig. 4 to engagement with terminal 86. At the moment of engagement, the motor 61 starts to operate to lower the valve stem 11 from the salt wash to the rinse position, as indicated in Fig. 6, leaving the mercoid switch 89 locked in closed circuit position by the latch 91 so that the timer 76 continues turning under operation of motor 75. The cam 72 maintains the circuit for the motor 61 when the brush 80 leaves the terminal 86 and keeps the motor 61 operating until the cam 64 has been moved through 90° whereupon the follower on the cam drops into the next notch and opens contacts 72', leaving the parts in the position illustrated in Fig. 6. Under these circumstances, the cam 70 having been moved through 270° from the position shown in Fig. 4 has closed contacts 70'. The rinse continues for that period of time that it takes for the brush 81 to travel from the position in Fig. 5 to the position shown in Fig. 6, which is approximately 270° of movement of the timer 76, as compared with approximately 90° of movement of the timer during the salt wash. When the brush 81 engages terminal 87 the circuit for motor 61 is again completed and the latter operates to turn

the cam 64 through another 90° of movement from the position shown in Fig. 6 back to the position shown in Figs. 2 and 4, to bring the valve back to softening position. The cam 72 again serves the purpose of maintaining the motor circuit intact after the brush 81 leaves the terminal 87, so as to insure continued operation of the motor 61 sufficient for 90° of movement of the cam 64, whereupon the follower on the cam 72 drops into the last notch and opens the contacts 72' to stop the motor. The cycle is then completed so far as the valve is concerned. However, the motor 75 is still running inasmuch as the mercoid switch 89 is still locked in raised position by latch 91. The timer 76, therefore, continues to turn until the pin 95 is moved from the position shown in Fig. 6 to that shown in Fig. 4, whereupon the latch 91 is moved to release the switch 89 so that the latter can drop down to the position shown in Fig. 4 and cause the motor 75 to stop. The cycle is then completed so far as the control mechanism is concerned and everything is left as illustrated in Fig. 4 for the period of softening, the cam 73 having closed contacts 73' so that the next cycle can be begun by simply closing the switch 74 when the softener requires regeneration.

The control mechanism is quite simple and compact in construction. It lends itself to combination with standard types of power operated mechanisms, such as the mechanism 60, and offers the advantage of adjustability so that one may shorten or lengthen the salt wash and do likewise with the rinse, so long as the total movement is kept within the 360° of movement of the timer. The reduction gearing at 77 provided between the motor 75 and the timer 76 is such that it will take say 30 minutes for the timer to make a complete turn, but these gears may be changed to shorten or lengthen this timer period. By proper adjustment of the brushes 80 and 81 this timer period may be divided as desired, as for example, into a 5 minute salt wash and a 20 minute rinse period, or more or less for each of said periods. The use of a mercoid switch 89 for making and breaking the circuit for motor 75 insures reliability and also durability. However, in view of the cost of such a switch and the fact that its use necessitates the mounting of the control mechanism on the other mechanism as hereinabove described, I contemplate providing as an alternative a mechanism such as disclosed in Fig. 7, which is more compact, less expensive, and may be mounted on the wall or at any other convenient place, without regard to the location of the valve and its operating mechanism.

Referring to Figs. 7 and 8, 75' is a self-starting clock type motor similar to the motor 75 previously described, driving a timer 76' through suitable reduction gearing. A casing 78' constitutes a housing for this mechanism and may be mounted on the wall or at any other convenient place with the wires extended thereto from the mechanism 60' for operating the valve. The timer 76' has two contact brushes 80' and 81' adjustably mounted on the rotatable body thereof, the former disposed in one plane and extending to a certain radius and arranged to be clamped in adjusted position by means of a thumb screw 82' entered in the arcuate slot 83', and the other disposed in another plane and projecting to a larger radius and arranged to be clamped in adjusted position by means of another thumb screw 84' entered in the arcuate slot

85'. The brush 80' is arranged to wipe and ride over a terminal 87' disposed at the proper radius with respect to the timer and reaching only to the plane of the brush 80'. Another terminal 86' cooperates with the brush 81' in a similar manner. The arrangement is such that the brush 80' will engage only the terminal 87', and the brush 81' will engage only the terminal 86' in the turning of the timer. Two brushes 89a and 89b ride on the periphery of the timer. These two brushes together accomplish the same purpose as the mercoid switch 89 in the other mechanism. The brush 89b has a broader end than the brush 89a so as to be disengaged from the timer by means of a finger 95' of insulating material mounted on the back of the timer. The brushes 89a and 89b are carried on a base 90' of insulation material. Now, the mechanism 60' is similar to the mechanism 60 previously described with the exception that another cam 71a is provided on the shaft 63 as a companion to the cam 71, both cams being arranged to close contacts 71' simultaneously in the first half turn of the shaft 63.

25 The operation of this mechanism is similar to that of the mechanism previously described. When the operator closes the switch 74, a circuit is completed through motor 61 by reason of the fact that the contacts 73' are at the time held closed by cam 73. After the motor is started, the circuit is kept intact by reason of closing of contacts 72' by cam 72. The shaft 63 is given a half turn, whereupon the follower engaging the cam 72 drops into the notch and opens the contacts 72'. The valve stem 11 has accordingly been raised from softening position to salt wash position. At the same time both sets of contacts 71' have been closed by cams 71 and 71a with the result that motor 75' is thrown into operation, its circuit being traceable through conductors 97 and 98. As the timer 76' turns under operation of motor 75', the finger 95' rides off the brush 89b and from that point on the circuit for the motor 75' is no longer dependent upon the closing of the contacts 71' and the motor 75' will accordingly operate for a complete turn of the timer 76', namely, until the finger 95' again reaches the brush 89b and causes its disengagement. The salt wash continues for that period of time that it takes for the brush 81' to travel from the position shown in Fig. 7 to engagement with terminal 86'. At the moment of engagement, the motor 61 starts to operate to lower the valve stem 11 from the salt wash to the rinse position. The cam 72 maintains the circuit for the motor 61 when the brush 81' leaves the terminal 86', and keeps the motor 61 operating until the cam 64 has been moved through 90° whereupon the circuit is again broken by the contact 72'. Under these circumstances, the cam 70 having been moved through 270° from the position shown in Fig. 7, has closed contacts 70'. The rinse continues for that period of time that it takes for the brush 80' to travel the remaining distance to engagement with terminal 87'. At the moment of engagement the motor 61 is again thrown into operation, and here again the cam 72 serves the purpose of maintaining the motor circuit intact after the brush 80' leaves the terminal 87', whereby to insure operation of the motor 61 sufficient for 90° of movement of the cam 64, whereupon the follower on the cam 72 drops into the last notch and opens the contacts 72' to stop the motor. This completes the

cycle so far as the valve is concerned, but the motor 78' continues to run until the finger 85' causes disengagement of the brush 89b from the timer 76'.

It is believed the foregoing description conveys a good understanding of my invention. The appended claims have been drawn with a view to covering all legitimate modifications and adaptations.

I claim:

1. In a control mechanism, an electrical valve operator adapted to reciprocate a valve stem through a succession of steps to open and close different ports in a valve for controlling a water softener, electrical timing means adapted to make one revolution and stop, said timing means having connections for energizing said operator to initiate each of said steps subsequent to the first, means for starting the electrical valve operator, and means operated by said valve operator to close an electric circuit to start the electrical timing means, said electrical timing means having means for opening the electric circuit when said timing means has made one revolution.

2. The combination in a control mechanism of a device to be operated repeatedly through a predetermined succession of movements in a cycle, a main motor for operating said device, a starting switch for said motor, a second motor set into operation by said first motor, timing means operated by said second motor for effecting successive starts of said first motor in a cycle in timed relation to the first start, during continuous operation of said second motor, said second motor being a synchronous motor whereby to accurately time the operation of said device, and means operated by said second motor for deenergizing said second motor at the completion of the cycle.

3. A control apparatus for a water treatment unit comprising a controlled device adapted to be operated periodically in a predetermined cycle of successive movements, an intermittently operable motor driven mechanism for power operation of said device, make and break means for determining the extent of operation of said mechanism during each successive movement, a starting switch for starting the cycle of operations of said mechanism whereby to start a cycle of movements of said device, a timer having electrical connections with the aforesaid mechanism for subsequently initiating in predetermined timed relationship the further operations of said mechanism in the cycle, a separate constant speed motor for driving the timer, a switch for closing the circuit through said motor operable in response to the first of said successive movements of said controlled device, said timer having switch contacts for maintaining the circuit through the motor to move the timer through a complete timing cycle, adjustable switch means for controlling the duration of different settings of said controlled device, and means driven by said motor for operating the switch contacts to open the circuit through the motor upon completion of the timing cycle.

4. A control apparatus comprising in combination a device adapted to be operated periodically in a predetermined cycle of movements, an intermittently operable motor driven mechanism for power operation of said device including a make and break means for predetermining the extent of operation thereof upon each initiation, a starting switch for starting the cycle of oper-

ations of said mechanism whereby to start a cycle of operations of said device, a timer having electrical connections with the aforesaid mechanism for subsequently initiating in a predetermined timed relationship the further operations of said mechanism in the cycle, a separate constant speed motor for driving the timer continuously in one direction during the cycle, a switch for closing the circuit through said motor operable automatically during the first movement of the cycle, said switch tending normally to move to open circuit position, means for releasably locking said switch in closed circuit position so as to keep the timer operating throughout the cycle of operations of said device, and means movable with the timer for releasing said switch after the cycle has been completed.

5. A valve control apparatus comprising, in combination, valve means having a reciprocable control stem, an intermittently operable motor driven mechanism for power operation of said control stem through a cycle of successive movements, the same having a reciprocable plunger for communicating movement to said stem, a starting switch for starting the cycle of operations of said mechanism whereby to start a cycle of valve movements, a timer having electrical connections with the aforesaid mechanism for subsequently initiating in a predetermined timed relationship the further operations of said mechanism in the cycle, the aforesaid mechanism including a make and break device for predetermining the extent of operation of the mechanism upon each initiation, a separate constant speed motor for driving the timer, and a pivotally mounted mercoid switch for closing and opening the main energizing circuit for said motor, said switch normally occupying an open circuit position and being arranged for movement to closed circuit position with movement of the plunger of the aforesaid mechanism during the first movement of said cycle.

6. The combination in a control apparatus for valves of the type having a reciprocating valve stem adapted to move longitudinally to open and close different ports therein, of a motor for driving said stem through a cycle in a succession of movements, automatic switch means operated in conjunction with said motor for controlling starting and stopping of the same, a second motor, automatic switch means operated thereby and electrically connected with said first motor and its switch means whereby to initiate each subsequent operation of said first motor and stem in said cycle in a predetermined timed relation to the first operation, and a mercoid switch movable from a normal open circuit position to a closed circuit position in response to the first of said successive movements of the stem whereby to start said second motor in timed relation to said first motor.

7. The combination as set forth in claim 6 including means for releasably locking said mercoid switch in closed circuit position and means for releasing said mercoid switch after completion of the cycle of movement of said first motor and said stem and return of said second mentioned switch means to the starting positions thereof.

8. A control apparatus comprising, in combination, a device adapted to be operated periodically in a predetermined cycle of movements, an intermittently operable motor driven mechanism for power operation of said device, a starting switch for starting the cycle of operations of

said mechanism whereby to start a cycle of operations of said device, a timer having electrical connections with the aforesaid mechanism for subsequently initiating in a predetermined timed relationship the further operations of said mechanism in the cycle, the aforesaid mechanism including a make and break means for predetermining the extent of operation of the mecha-

nism upon each initiation, a separate constant speed motor for driving the timer, and a switch for closing the circuit through said motor operable automatically in the first movement of said device at the commencement of the cycle to drive said timer through a timing cycle.

LEE G. DANIELS.
